O. BORGUET ET AL

ROOF FOR SHEDS, RAILWAY STATIONS, TERMINALS, AND THE LIKE

FIG. 1

FIG. 2

FIG. 3

FIG. 4

FIG. 5

Inventors:

Octave Borguet
and Maurice Borguet
By *Louis Reinisch*
Attorney.

UNITED STATES PATENT OFFICE.

OCTAIVE BORGUET AND MAURICE BORGUET, OF BRAIM-LE-COMTE, BELGIUM.

ROOF FOR SHEDS, RAILWAY STATIONS, TERMINALS, AND THE LIKE.

Application filed December 5, 1923. Serial No. 678,642.

To all whom it may concern:

Be it known that we, OCTAIVE BORGUET and MAURICE BORGUET, subjects of the Kingdom of Belgium, residing at Braim-le-Comte, Belgium, have invented certain new and useful Improvements in Roofs for Sheds, Railway Stations, Terminals, and the like, of which the following is a specification.

The present invention relates to economical roofs for sheds, and particularly to roofs for train sheds as employed at railway stations, terminals and the like; and the object thereof is to provide means for gases, vapors and smoke to pass outwards into the open air while at the same time preventing rain or snow from passing therethrough into the shed.

The train sheds ordinarily constructed are of great height in order to permit the diffusion of smoke, so that they are consequently expensive in installation and maintenance, because of the corroding action of the smoke and the gases.

According to the invention the ducts necessary for directly evacuating the gases are disposed in such a manner that their lateral walls or their supporting elements form the longitudinal girders supporting the roof. These girders are supported at great distances apart on transverse curved beams in the case of train sheds or on walls in the case of locomotive sheds.

The hereinafter described ducts may be composed of metal, reinforced concrete, or any other desired material calculated to withstand the corroding action of the gases. According to another object of the invention the ducts may communicate by means of several conduits with a collector, wherein a predetermined rarefaction is maintained, each of the conduits being controlled by a register.

Our invention is fully described in the following specification and is illustrated in the accompanying drawings, in which the separate elements are designated by the same reference characters in each of the views and in which:

Figure 1 is a perspective view of the upper part of a train-shed constructed according to our invention and wherein some of the elements are sectioned.

Figure 2 is a transverse section through a train shed.

Figure 3 is a variation of Figure 1. 55

Figure 4 shows a fragmentary elevation of a train shed with a central collector.

Figure 5 is a transverse section through a locomotive shed.

In the said drawings, we have shown a train shed comprising an arched roof provided with longitudinally arranged ducts 2 disposed over the tracks and serving for smoke, gases, vapors and vitiated air to pass outward into the open air. The lateral walls 1 of these ducts form the girders on which bears the roof that can be otherwise suitably supported. According to Figure 2, the longitudinal ducts 2, disposed over the tracks communicate upwards with the open air by means of a central common passage 5. According to Fig. 3, the longitudinal ducts 2 communicate with the open air by means of a plurality of chimneys 3, disposed at some distance from each other along the shed.

According to Figure 4, the ducts 2 disposed over twin tracks communicate at their upper part by means of conduits 7 with a common collector 8 which extends the length of the shed. The conduits 7 are provided with valves or registers 9 permitting the regulation of the draughts of air formed by the rarefaction existing in the collector 8. The latter preferably has the form of a trough, at one end of which an exhaust fan is located, and it is the operation of this fan which creates the rarefaction in the collector referred to above. The valves or registers 9 obviously control the extent of such rarefaction according to the position to which they are moved in the conduits 7, their adjustment being effected by means of chains or the like operated from a footbridge 10 or from the floor. The fan and 95 the valves 9 may be of any suitable type and in themselves form no part of the invention, for which reason further description of their structural details is considered unnecessary.

According to Fig. 5, the ducts disposed over each of the tracks and extending the length of the shed, are supported on one side on the cross-beam of the doors and on the other side on the end wall of the shed, 100

It will be apparent that many modifications of the same may be made in order to accomplish the desired results and reserving the right, to all such changes and modifications of the form shown and described.

What we claim as new and desire to secure by Letters Patent is:

1. A train shed or the like, having a roof which is provided with a pair of longitudinal ducts for evacuating gases, vapors and smoke, said ducts being arranged in spaced relation to each other and each paralleling and directly overlying a train track; a collector disposed between said ducts and in regulatable communication with the upper parts thereof at points along its length; and means for creating a predetermined rarefaction in said collector.

2. A train shed or the like, having a roof which is provided with a pair of longitudinal ducts for evacuating gases, vapors and smoke, said ducts being arranged in spaced relation to each other and each paralleling and directly overlying a train track; a collector disposed between said ducts; means for creating a predetermined rarefaction in the collector; a plurality of conduits leading from opposite sides of said collector to said ducts to establish communication between the same; and adjustable valves in said conduits to control such communication.

3. A train shed or the like, comprising longitudinal ducts, coextensive in length with the shed, for evacuating gases, vapors and smoke, which ducts are arranged in spaced relation to one another and each of which parallels and directly overlies a train track; said ducts embodying spaced, parallel side walls forming longitudinal girders, on the upper edges of which the roof of the shed directly rests.

4. A train shed or the like, having a roof which is provided with a pair of longitudinal ducts for evacuating gases, vapors and smoke, said ducts being arranged in spaced relation to each other and each paralleling

and directly overlying a train track; and a longitudinal outlet chamber disposed between and parallel with both ducts and in communication with the same, said chamber also communicating with the atmosphere.

5. A train shed or the like, comprising a plurality of longitudinal ducts, coextensive in length with the shed, for evacuating gases, vapors and smoke, which ducts are arranged in pairs in spaced relation to each other, each duct paralleling and directly overlying a train track; and a longitudinal outlet chamber individual to each pair of ducts and disposed between the same in parallel relation thereto and in communication therewith, each chamber also communicating with the atmosphere; the lateral walls of said ducts forming the longitudinal girders whereon the roof of the shed directly rests.

6. A train shed or the like, comprising a plurality of longitudinal ducts, coextensive in length with the shed, for evacuating gases, vapors and smoke, which ducts are arranged in pairs in spaced relation to each other, each duct paralleling and directly overlying a train track; a longitudinal chamber individual to each pair of ducts and disposed between and parallel with the same; means for creating a predetermined rarefaction in said chambers; a plurality of conduits leading from opposite sides of each chamber to the adjacent ducts to establish communication therebetween; and adjustable devices for controlling such communication; the lateral walls of said ducts forming the longitudinal girders whereon the roof of the shed directly rests.

In testimony, whereof we affix our signatures.

OCTAVE BORGUET.
MAURICE BORGUET.
